TIRE

Raymond W. Evans, Jr., Cuyahoga Falls, Ohio, assignor
to The B. F. Goodrich Company, New York, N.Y.,
a corporation of New York

Filed Mar. 20, 1968, Ser. No. 11,064

Term of patent 14 years

Int. Cl. D12—14

U.S. Cl. D90—20

The figure is a perspective view of a tire showing my new design.

It is to be understood that the tread pattern continues as shown throughout the circumference of the tire, and the sidewall opposite that shown is a mirror image thereof.

I claim:

The ornamental design for a tire, substantially as shown and described.
